UNITED STATES PATENT OFFICE.

NOAH BENJIMAN BIGGS, OF WICHITA, KANSAS, ASSIGNOR TO FRED J. ANTHONY, OF WICHITA, KANSAS.

DERRICK.

Application filed July 28, 1925. Serial No. 46,666.

This invention relates to derricks and has for its object the provision of a device having such knock-down characteristics that the same may be readily assembled or disassembled when desired without the destruction of any part.

Another object of the invention is the provision of a combination gusset and T-plates for removably fastening the girders 10 and corner posts in rigid relation.

A further object of the invention is the provision of a derrick constructed in sections and formed of a plurality of elements which are interchangeable in the various 15 sections for constructing the derrick of any desired height.

This invention will be best understood from a consideration of the following detailed description, in view of the accompanying drawing forming a part of the specification; nevertheless it is to be understood that the invention is not confined to the disclosure, being susceptible of such changes and modifications which shall define no material departure from the salient 25 features of the invention as expressed in the appended claims.

In the drawings:

Figure 1 is a side view in detail of a form 30 of connecting means for the girders and corner posts.

Figure 2 is a vertical section of the device shown in Figure 1.

Figure 3 is a horizontal section of the 35 connecting means shown in Figures 1 and 2 taken along the line 3—3 of Figure 1.

Figure 4 is a view in perspective of the T-plate.

Figure 5 is a side elevation in detail of 40 another form of the connecting means for the corner posts and girders.

Figure 6 is a plan view of the same.

Referring to Figures 1 to 4 inclusive a pair of corner posts 1^a are shown in abutting relation having their ends located in sockets of a key plate 20. Said key plate is provided with a pair of walls 21 and 22 connected together at a corner of the key plate and projecting above and below the upper and lower surfaces of said plate and integrally formed with two adjacent edges of said plate. The opposite adjacent edges are provided with keys 23 and 24 which project above and below the surfaces of the 55 plate 20 with the inner wall of the keys be-

ing flush with an edge of the plate 20 so that the keys project beyond said edges of the plate. The key plate and abutting ends of the post 1^a are embraced by a gusset plate 25 having a pair of side walls 26 and 27 located at right angles to each other. The said side walls are provided with openings 28 and 28^a adapted to receive either of the keys 23 or 24.

A U-shaped bracket 29^a is secured to each 65 face 26 or 27 of the gusset plate 25 adjacent their outer edges and are adapted to receive the ends of a girder 29. A stop 30 is secured adjacent the inner edge of each wall of the gusset plate and adapted to receive the inner 70 end in abutting relation of the girders 29. It will also be noted that the U-shaped bracket or guide 29^a has its outwardly projecting sides 31 located at an acute angle to the horizontal so that when the girders 75 29 are placed in position the girders will be located at an acute angle to the horizontal. The stops 30 are provided with a lip 32 adapted to engage over a girder 29 and maintain the same in position.

The side walls 26 and 27 at their upper and lower portions and adjacent the outer free edges of the side walls are formed elongated slots 33 adapted to receive a hook on the ends of a tie rod. The flanges 34 of 85 the U-shaped brackets 29^a are adapted to be secured to the side walls in any approved manner. The upper portion of the connection between the side plates 26 and 27 of the gusset plate 25 is cut away as 90 shown at 35 to form a slot to receive a bolt 36, the bolt being passed through a diagonally disposed passage in one of the corner posts 1^a.

Referring to Figures 5 and 6 the key plate shown in the previous figures is likewise employed with the gusset plate 25^a, the gusset plate being provided with the usual elongated slots 33 and a slot 35 to receive a bolt 36 which passes through the slot and diagonally through a corner post 1^a. A sheath 40 100 is secured at its opposite ends to the side plates 26 and 27 of the gusset plate 25^a and has an angular connecting member as shown at 41 for receiving the ends of the girders 29. The sheath comprises a top plate 42 and 105 side walls or flanges 43 which space the top plate from the walls of the gusset plate 25^a to receive the girders 29. The keys 23 and 24 are received within openings 28^a in the side walls of the gusset plate.

What I claim is:

1. An element of a derrick construction comprising means for securing the abutting ends of corner posts and girders in locked relation and comprising an angle iron having a pair of side walls disposed at right angles to each other, stops secured to the outer faces of the walls, a bracket secured to each wall adapted to receive the end of a girder with the end of the girder abutting the stops, and a key plate received between the walls of the angle iron and having sockets at its opposite faces to receive the abutting ends of the corner posts, the brackets on the side walls being located above the stops whereby the girders are supported at an angle to the horizontal.
- 10 5 15 20 25 30 35 40 45 50 55 60 65 70 75 80
2. An element of a derrick construction comprising means for securing the abutting ends of corner posts and girders in locked relation and comprising an angle iron having a pair of side walls disposed at right angles to each other, stops secured to the outer faces of the walls, a bracket secured to each wall adapted to receive the end of a girder with the end of the girder abutting the stops, and a key plate received between the walls of the angle iron and having sockets at its opposite faces to receive the abutting ends of the corner posts, the side walls of the angle iron being provided adjacent its outer free end with elongated slots, the axis of which being at an acute angle to the opposite edges of said side walls, said slots being adapted to receive the ends of tie rods.
3. An element of a derrick construction comprising means for securing the abutting ends of corner posts and girders in locked relation and comprising an angle iron having a pair of side walls disposed at right angles to each other, stops secured to the outer faces of the walls, a bracket secured to each

wall adapted to receive the end of a girder with the end of the girder abutting the stops, a key plate received between the walls of the angle iron and having sockets at its opposite faces to receive the abutting ends of the corner posts, the brackets on the side walls being located above the stops whereby the girders are supported at an angle to the horizontal.

4. An element of a derrick construction comprising means for securing the abutting ends of corner posts and girders in locked relation and comprising an angle iron having a pair of side walls disposed at right angles to each other, stops secured to the outer faces of the walls, a bracket secured to each wall adapted to receive the end of a girder with the end of the girder abutting the stops, and a key plate received between the walls of the angle iron and having sockets at its opposite faces to receive the abutting ends of the corner posts, the side walls of the angle iron being provided adjacent its outer free end with elongated slots, the axis of which being at an acute angle to the opposite edges of said side walls, said slots being adapted to receive the ends of tie rods.

5. An element of a derrick construction comprising an angle iron plate having a pair of walls at right angles to each other, said side walls being provided with elongated slots, a key plate interposed between the opposite ends of the angle irons and adapted to receive the abutting ends of corner posts, keys projecting from the adjacent edges of the key plate and adapted to be seated within the slots in the side walls of the angle irons, a sheath provided with pairs of laterally projecting flanges secured to each side wall of the angle iron and to receive the adjacent ends of a pair of abutting girders.

NOAH BENJIMAN BIGGS.
